US0D1007501S

(12) **United States Design Patent** (10) **Patent No.:** **US D1,007,501 S**
Ye (45) **Date of Patent:** **** Dec. 12, 2023**

(54) **COMPUTER**

(71) Applicant: **Lenovo (Beijing) Co., Ltd.**, Beijing (CN)

(72) Inventor: **Yizhou Ye**, Beijing (CN)

(73) Assignee: **Lenovo (Beijing) Co., Ltd.**, Beijing (CN)

(**) Term: **15 Years**

(21) Appl. No.: **35/514,008**

(22) Filed: **Dec. 30, 2021**

(80) **Hague Agreement Data**

Int. Filing Date: **Dec. 30, 2021**

Int. Reg. No.: **DM/219870**

Int. Reg. Date: **Dec. 30, 2021**

Int. Reg. Pub. Date: **Apr. 8, 2022**

(30) **Foreign Application Priority Data**

Sep. 30, 2021 (CN) 202130656394.7

(51) **LOC (14) Cl.** **14-02**

(52) **U.S. Cl.**

USPC **D14/314**; D14/355

(57) **CLAIM**

The ornamental design for a computer, as shown and described.

DESCRIPTION

Computer

3.1 is a front view of a computer showing the new design;

3.2 is a back view thereof;

3.3 is a left view thereof;

3.4 is a right view thereof;

3.5 is a top view thereof;

3.6 is a bottom view thereof; and

3.7 is a perspective view thereof.

The broken lines shown in the drawings illustrate portions of the computer that form no part of the claimed design.

1 Claim, 7 Drawing Sheets
